UNDERGARMENT FOR WOMEN AND GIRLS

Malcolm Feiner, Brooklyn, N. Y.

Application April 8, 1935, Serial No. 15,212

7 Claims. (Cl. 2—73)

This invention relates to undergarments for women and girls, particularly to the type of undergarment known as a slip.

Broadly, it is the object of this invention to provide an undergarment of very simple construction, making it economical to manufacture, at the same time creating a perfectly fitted undergarment, pleasing in appearance, which will hang properly at all times and allow for the movements of the limbs and body of the wearer.

Specifically, it is an object of this invention to eliminate all seams and provide for only a V joint in the rear, so that no ridges appear at the hip-line, it being desirable that a slip that is worn with a closely fitted dress should hang straight and against the body of the wearer and that no ridges created by seams should be noticeable, so that the outer garment will fit smoothly and snugly. Undergarments made with seams do not readily adjust themselves to the different types of figures of women and girls, especially where such seams appear at the sides and front.

A distinct feature is the method of cutting of practically the entire garment in one piece, including a shadow-proof panel, with the exception of a small V-shaped triangle on the back, so that the cost of the sewing operations in the construction of the slip is greatly decreased.

A further object of this invention is the cutting of the material so that the entire slip will be set on a bias, thereby giving the entire undergarment a maximum of stretchability, insuring perfect freedom of movement to the wearer, and having sufficient elasticity so that the slip will adjust itself upon the body of the wearer in its normal and proper position.

These and other advantages, capabilities and features of the invention will appear from the subjoined detailed description and more particularly pointed out in the claims appended hereto.

In the accompanying drawing, which illustrates a practical embodiment of my invention

Figure 1 is a front view of the undergarment or slip indicated as worn on a model.

Figure 2 is a rear view of the same.

Figure 3 illustrates the pattern of the main part of the slip.

Figure 4 illustrates the pattern of the small portion inserted in the back of the slip.

Figure 5 illustrates a side view of the undergarment, the small triangular back portion being eliminated and the shoulder straps attached to the rear upper edges.

Referring to the reference characters in the drawing, numeral 10 in Figure 1 indicates the

main body portion of the undergarment, which consists of an entire single piece of material extending from approximately the bustline to the bottom edge of the slip and around the entire figure of the wearer.

In the cutting of the slip the pattern of the main body portion 10 as shown in Figure 3 is placed on the woven material 11 so that the edges 12 and 13 of the pattern run parallel to the selvage edges 14 and 15 of the material 11 and the warp threads, as indicated by a single warp thread 16. The edges of the pattern 17 and 18 run parallel to the filler or weft threads of the material 11, as indicated by single thread 19. The traverse bias line is indicated by the broken line 20 which bisects the 90° right angles formed by the warp and filler or weft threads of the material.

In the construction of the slip, the material is folded so that the portions adjacent the edges 12 and 18 are disposed in overlapping relation. The edges 38 and 39 are disposed in alinement and are stitched along the line 40, as shown in Figure 2. The overlapping edge portions above referred to form a shadow proof panel below the point of intersection of the edges 13 and 17. The side edges 12 and 18 are stitched to the body portion along the lines 41 and 42 as also clearly shown in Figure 2. In some slips it may be desirable not to stitch the longer edges of the shadow-proof panel, leaving such edges open to give greater facility of movement. It is obvious that extensions 21 and 22 can be eliminated and the side edges cross in the back to form the shadow proof panel 23 below the point of intersection. There is inserted for a back portion a piece of material 25, having its diverging edges 26 and 27 joined with stitching to edges 17 and 13 of the main body portion 10. The piece of material 25 has its warp threads, as indicated by the single line 28, and filler or weft threads, as indicated by the single line 29, running at angles of 90° to each other, and at 45° angles to the bias line, as indicated by the broken line 30, and it is joined to the main body portion 10 so that the bias line 30 is in a vertical position when the slip is on the wearer. For the purpose of economy, the back portion 25 may be cut from the material 11 as indicated in Figure 3, so that the bias line 30 will run in the same direction as bias line 20, as shown in Figure 3, when joined at the rear of the slip. It may be desirable, for use with some type of evening gowns, to eliminate the triangular piece 25, creating a backless slip, as shown in Figure 5.

Shoulder straps 31 and 32, as shown in Figures 1 and 2, are secured to the slip from points 33 and 34, as shown in Figures 1 and 3, and at the back portion 25 to the edge 35 at approximately 5 the points 36 and 37, as shown in Figure 2. In the event a backless slip is desired, these shoulder straps are secured at the back to the V-shaped sides of the main body portion.

As will be seen in Figures 1 and 2, the main 10 body portion 10 of the material, and the small substantially triangular portion 25, which comprise the garment, are so arranged that the entire garment is composed of material which is cut on a bias with respect to the vertical axis of the slip, 15 thereby having the desirable feature of maximum stretchability in order to give perfect freedom of movement to the wearer, at the same time decreasing the wear upon the slip, because the transverse strain is materially reduced.

20 The slip, being wholly of bias-cut construction, closely hugs the body of the wearer, so that the outer garment hangs properly and fits smoothly and snugly upon the person, all unsightly ridges near the hipline and the sides having been eliminated so that a closely fitted dress will hang straight and have a more pleasing appearance.

An additional advantage of an entirely bias-cut slip is that it will automatically fit and conform 30 itself to the body of the wearer, and because of 30 its elasticity, adjust itself into a normal position after different movements of the person.

It is obvious that various changes and modifications may be made to the details of construction without departing from the general spirit of 35 the invention as set forth in the appended claims.

I claim:

1. In a garment of the class described, comprised of a body portion made of a single piece of material, said body portion being substantially 40 triangular in shape and having a curved base, the top of said triangular body portion covering the busts of the wearer, the side edges extending under the arms and crossing in the back and being connected together at their point of intersection, the side edge portions overlapping below the point of intersection and forming a shadow proof panel.

2. In a garment of the class described, comprised of a body portion made of a single piece of material, said body portion being substantially 50 triangular in shape and having a curved base, the side edges extending substantially at right angles to each other and substantially parallel with the threads of the fabric, the top of said 55 triangular body portion covering the busts of the wearer, the side edges extending under the arms and crossing in the back and being connected together at their point of intersection, the side edge portions overlapping below the point of intersection and forming a shadow proof panel whereby an entirely bias form fitting garment is obtained.

3. In a garment of the class described, comprised of a body portion made of a single piece 65 of material, said body portion being substantially triangular in shape and having a curved base, the top of said triangular body portion covering the busts of the wearer, the side edges extending under the arms and crossing in the back 70 and being connected together at their point of intersection, the side edge portions overlapping

below the point of intersection and forming a shadow proof panel, said side edges being joined to the body of the garment below the aforesaid point of intersection, and a small triangular portion inserted in the back.

4. In a garment of the class described, comprised of a body portion made of a single piece of material, said body portion being substantially triangular in shape and having a curved base, 10 the sides of said body portion having extensions in the lower portions, the top of said triangular body portion covering the busts of the wearer, the side edges extending under the arms and crossing in the back and being connected together at their point of intersection, the side 15 edge portions overlapping below the point of intersection and forming a shadow proof panel, said side edges being joined to the body of the garment below the aforesaid point of intersection.

5. In a garment of the class described, comprised of a body portion made of a single piece of material, said body portion being substantially triangular in shape and having a curved base, 20 the top of said triangular body portion covering the busts of the wearer, the side edges extending under the arms and crossing in the back forming a V-shaped opening above the point of intersection, the side edges being connected together at their point of intersection, the side 25 edge portions overlapping below the point of intersection and forming a shadow proof panel, said side edges being joined to the body of the garment below the aforesaid point of intersection, and a small triangular portion inserted in the back and joined to the edges of the said V-shaped opening formed above the point of intersection.

6. In a garment of the class described, comprised of a body portion made of a single piece of material, said body portion being substantially 30 triangular in shape and having a curved base, the top of said triangular body portion covering the busts of the wearer and the sides having extensions in the lower portions, said side edges extending under the arms and crossing in the 45 back forming a V-shaped opening above the point of intersection, the side edges being connected together at their point of intersection, the side edge portions overlapping below the point of intersection and forming a shadow proof panel, 50 the side edges of said extensions being joined to the body of the garment below the aforesaid point of intersection, and a small triangular insert joined to the edges of the said V-shaped opening forming a back whereby an entirely bias 55 form fitting garment is obtained.

7. In a garment of the class described, comprised of a body portion made of a single piece of material, said body portion being substantially triangular in shape and having a curved base, 60 the top of said triangular body portion covering the busts of the wearer, the side edges extending under the arms and crossing in the back and being connected together at their point of intersection, the side edge portions overlapping below the point of intersection and forming a shadow proof panel, said side edges being joined to the body of the garment below the aforesaid 65 point of intersection.

MALCOLM FEINER. 70
